UNITED STATES PATENT OFFICE.

RICHARD B. MARSH, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

CAR-SEAT.

1,184,113.

Specification of Letters Patent. Patented May 23, 1916.

Application filed January 24, 1913. Serial No. 743,886.

To all whom it may concern:

Be it known that I, RICHARD B. MARSH, a citizen of the United States, residing at Philadelphia, in the county of Philadelphia and State of Pennsylvania, have invented certain new and useful Improvements in Car-Seats, of which the following is a specification.

This invention relates to car-seats and is directed to the provision of an improved mechanism whereby the seat-cushion of such a seat is moved from one to the other of two operative positions when the back-cushion is moved from one edge to the other of the seat-cushion in reversing the facing direction of the seat.

The object of the invention is to provide a cushion-moving mechanism of this character which, while being simple in construction, possessing great strength and being capable of manufacture at low cost, will occupy but little space and, particularly, will extend downwardly from the seat-cushion but a small amount.

In the construction of seats for use in railway cars, it is desirable that the maximum space be provided below the seat-cushion, and this is particularly true with respect to the space at the end of a car-seat adjacent to the wall of the car, for it is common to utilize this space for the steam pipes which run lengthwise of the car and form part of the heating system of the car. In many forms of car-seats as heretofore made, the space under the seat-cushion at the wall end of the seat has not been as great as has been desired because of the space required for the mechanism by which the seat-cushion is moved when the back is reversed. In accordance with the present invention, the seat-moving mechanism is so constructed and arranged that it does not encroach upon the space under the seat-cushion and below the supporting structure of the seat.

I have illustrated the preferred embodiment of my invention in the accompanying drawings, in which—

Figure 1 is an elevation of one end of a car-seat constructed in accordance with the invention, Fig. 2 is an enlarged detail view of certain of the parts shown in Fig. 1, and Fig. 3 is a plan view of one end of the seat, certain of the parts being removed for the sake of clearance.

Referring to these drawings, the car-seat is shown as consisting of a back-cushion 4 and a seat-cushion 5, these being mounted upon a suitable supporting structure including a pedestal 6, a seat-end 7, and two connecting rails 8. In the present instance the pedestal 6 is shown as constructed of sheet-metal, and the seat-end 7 is shown as integral with one of the parts of the pedestal.

The back-cushion 4 is mounted upon back-supporting arms 9, each of which is adapted to travel upon an arc-shaped rail 10 which is secured to the inner side of the seat-end 7. In this way the back-cushion may be moved from one edge of the seat-cushion to the other to reverse the facing direction of the seat.

The back-supporting arm 9 has a slot 11 therein which receives a pin on one end of a lever 12 which is secured to a rock-shaft 13, mounted in bearings formed in the seat-ends. When the back-cushion is moved from one position to the other, the shaft 13 is rocked in its bearings by means of the levers 12. This rock-shaft serves to connect the mechanisms at the two ends of the seat so as to insure synchronous movement of the parts at both ends and, furthermore, the movement of the rock-shaft is utilized to cause the shifting of the seat-cushion.

A support 14 is provided between two connecting rails 8, this support being in the form of a sheet-metal strip having its ends bolted or riveted to the rails 8. This support forms a track upon which a member of the seat-moving mechanism is adapted to be reciprocated. This member is here shown as a block 15 which rests upon the strip 14 and is provided with headed studs 16 extending through a slot 17 in the strip 14. The block 15 is provided with a vertically-disposed way or groove 18 in one side thereof which is adapted to receive a stud or projection 19 formed on the end of a crank arm 20 which is secured to the rock-shaft 13. Thus, when the rock-shaft is rocked in its bearings, the crank arm 20 will cause the block 15 to be moved in a straight line upon the surface of the strip 14.

The block 15 has a lever 21 pivotally mounted thereon, the lever 21 being on the side of the block opposite the crank arm 20. At one end this lever 21 is provided with a stud 22 which enters a vertically-disposed slot 23 in a rocker 24. This rocker is supported upon the connecting rails 8 and forms

the support for the seat-cushion 5, the rocker being provided with pins 25 which enter openings in the frame of the seat-cushion. The lever 21 is provided with a slot in the 5 end thereof opposite that on which the pin 22 is formed, and the walls of this slot lie on either side of the rock-shaft 13.

As above pointed out, when the back-cushion is moved from one edge to the other 10 of the seat-cushion, the rock-shaft 13 is rocked in its bearings and as a result of this rocking movement the block 15 is moved in a straight line over the surface of the support 14. This movement of the block 15 causes 15 a shifting of the pivot of the lever 21. At the same time that this shifting of the pivot of the lever 21 takes place, that lever is caused to turn about its pivot, for one end of the lever is in coaction with the rock-shaft 13. The opposite end of the lever 21, that is, the end which is connected to the 20 rocker 24, is therefore given a movement resulting in part from the lateral shifting of the pivot of lever 21, and in part from the movement of the lever about its pivot. In 25 this way the requisite amount of movement of the rocker 24 is obtained even though the lever 21 is quite short. By reference to the drawings, and particularly to Fig. 2, it will 30 be seen that the mechanism for effecting the shifting of the seat-cushion as the back-cushion is reversed is very compactly arranged. As here shown, none of the parts of this seat-moving mechanism extends 35 below the plane of the lower edges of the connecting rails. As a result of this all of the space below the connecting rails is available for other uses, and particularly for the steam pipes employed in heating the car.

40 It is to be understood that various modifications may be made in the construction herein illustrated and described, without departing from the invention, and that all such modifications I aim to include within 45 the terms of the appended claims. Particularly, I wish it understood that the invention is not limited with respect to the type of mechanism by which the back-cushion is supported and by which provision is made 50 for movement of the back-cushion. The mechanism herein shown for this purpose is chosen merely to illustrate a mechanism which will serve this purpose and which 55 may be employed in connection with my improved seat-moving mechanism.

Having described my invention, what I claim as new therein and desire to secure by Letters Patent of the United States is:

60 1. In a car-seat, the combination of a seat cushion, a back-cushion, and means for moving the seat cushion as the back cushion is moved, comprising a rocker on which the seat-cushion is mounted, a member arranged 65 to reciprocate parallel to the length of the rocker, means actuated by the movement of

the back for reciprocating said member, a lever pivoted intermediate its ends on said member, with its pivot movable therewith in the reciprocation of said member, said lever engaging the rocker on one side of its pivotal connection with said member, and fixed means slidingly engaging said lever on the other side of its said pivotal connection, substantially as set forth.

2. A car-seat comprising the combination 75 of side-frames, rockers mounted thereon, a rock-shaft journaled in the side-frames, a seat-cushion mounted on the rockers, a back-cushion mounted on the side-frames and 80 movable from one edge of the seat-cushion to the other, connections from the back-cushion to the rock-shaft for causing the movement of the former to rock the latter, a member mounted to reciprocate in the direction of the length of the rocker, a crank 85 on the rock-shaft engaging said member and reciprocating the same as the rock-shaft is rocked, a lever pivoted to said member and connected to the rocker, and means for causing the lever to turn on its pivot as said 90 member is reciprocated, substantially as set forth.

3. A car-seat comprising the combination 95 of side-frames, rockers mounted thereon, a rock-shaft journaled in the side-frames, a seat-cushion mounted on the rockers, a back-cushion mounted on the side-frames and 100 movable from one edge of the seat-cushion to the other, connections from the back-cushion to the rock-shaft for causing the movement 105 of the former to rock the latter, a member mounted to reciprocate in the direction of the length of the rocker, a crank on the rock-shaft engaging said member and reciprocating the same as the rock-shaft is rocked, and a lever pivoted to said member, connected to the rocker on one side of the pivot 110 of the lever and guided by sliding contact with the rock-shaft on the other side of the pivot of the lever, substantially as set forth.

4. A car-seat comprising the combination 115 of side-frames, rockers mounted thereon, a rock-shaft journaled in the side-frames, a seat-cushion mounted on the rockers, a back-cushion mounted on the side-frames 120 and movable from one edge of the seat-cushion to the other, connections from the back-cushion to the rock-shaft for causing the movement of the former to rock the latter, a member mounted to reciprocate in the direction of the length of the rocker, a crank on the rock-shaft engaging said member and reciprocating the same as the rock-shaft is rocked, and a lever pivoted on said member, having a pin and slot connection 125 with said rocker on one side of the pivot of the lever and provided with a slot on the other side of the pivot of the lever in which slot said rock-shaft lies, substantially as set forth.

5. A car-seat comprising a seat-cushion, a back-cushion movable from one side to the other of the seat-cushion, a supporting structure for the cushion including a pair of connecting rails, a rocker mounted on the rails and supporting the seat-cushion, a support extending between and secured to the rails, a member slideable upon said support as the back-cushion is moved, a lever pivoted to 10 said member intermediate its ends with its pivot thereon movable with said member in the sliding movements of the latter, a connection between said lever and said rocker, and means for causing said lever to turn on 15 its said pivot as said member is moved upon said support, substantially as set forth.

6. In a car-seat, means for moving the seat-cushion as the back-cushion is moved comprising a pivoted lever engaging the 20 seat-cushion structure to move the same, means for shifting the pivot of the lever as the back-cushion is moved, and means for causing the lever to turn about its pivot as its pivot is shifted, substantially as set forth.

25 7. In a car-seat, means for moving the seat-cushion as the back-cushion is moved comprising a rocker for the seat-cushion, a vertically-disposed pivoted lever having a pin and slot connection to the rocker, 30 means for shifting the pivot of the lever as the back-cushion is moved, and means for causing the lever to turn about its pivot as its pivot is shifted, substantially as set forth.

35 8. In a car-seat, means for moving the seat-cushion as the back-cushion is moved comprising a rocker for the seat-cushion, a rock-shaft which is rocked in its bearings when the back-cushion is moved, a pivoted 40 lever engaging said rocker and said rock-shaft, and means actuated by the rocking of

the rock-shaft for shifting the pivot of said lever, substantially as set forth.

9. In a car seat, means for moving the seat-cushion as the back-cushion is moved, 45 comprising a lever having a pin and vertical slot connection at one end with the seat-cushion, means for guiding the opposite end of said lever in a vertical arc, while permitting oscillation of the lever about that end, 50 and means for applying pressure to said lever at a point intermediate its ends, as the back-cushion is moved, to cause the oscillation thereof about said guiding means, substantially as set forth. 55

10. In a car seat, the combination of a seat-cushion, a back-cushion movable from one side to the other of the seat-cushion, a supporting structure for the seat-cushion including connecting-rails, a rocker mounted 60 on the rails and supporting the seat-cushion, a support extending between and secured to the rails, a member horizontally slideable upon said support, means extending above said connecting-rails for moving said member when the back-cushion is moved, a lever pivoted to said member intermediate its ends, and having one end pivotally connected to the rocker, and the other end extending above the plane of said connecting 65 rails, and restraining means coacting with said last-mentioned end as said member is moved, to cause movement of said end about the said intermediate pivot of said lever as a center, substantially as set forth. 70 75
